MATERNITY GARMENT

Ruth M. Mahoney, Santa Monica, Calif.

Application October 25, 1945, Serial No. 624,453

2 Claims. (Cl. 2—76)

1

My invention relates to a maternity garment and an important object is to have such a garment that comprises a skirt that will continue to hang properly across the front with the progressive expansion of the wearer's girth.

Another object of the invention is to provide complete freedom of expansion in such a garment, around the girth.

A further object is to provide a maternity garment in which the distance from the shoulders to the waistline may be progressively lengthened during the pregnancy period.

Still another object in a garment of the character described is that the weight thereof may be carried from the shoulders of the wearer.

My invention also has for its objects to provide such a garment that is at all times comfortable to wear, convenient to put on and take off, economical to make, relatively simple and of general superiority and serviceability.

The invention also comprises novel details of construction and novel combinations and arrangements of parts, which will more fully appear in the course of the following description. However, the drawings merely show and the following description merely describes one embodiment of the present invention, which is given by way of illustration or example only.

In the drawings, like reference characters designate similar parts in the several views.

Fig. 1 is a front elevational view of a garment embodying the foregoing objects, shown in a partially expanded position.

Fig. 2 is a side elevational view of same.

Fig. 3 is a side elevation showing the garment in a normal or non-expanded position.

Fig. 4 is a side elevation of the garment without the front portion of the skirt.

Fig. 5 is an enlarged section taken on the line 5—5 of Fig. 1.

Fig. 6 is an enlarged section taken on the line 6—6 of Fig. 2.

In the drawings the garment is shown without sleeves since the sleeves may be of any desired shape, size or style, or may be omitted entirely.

Referring more in detail to the drawings, the reference number 7 generally indicates the back portion of a maternity garment. A front portion, which is really the front portion of the waist or bodice, is indicated at 8 and as being stitched to the back portion 7 along the sides by seams 9. Seams 10 connect the back and front portions to each other on the shoulders.

The normal waistline is suggested at 12 in Fig.

4. The back portion 7 is intended to form the back portion of the garment to the lower hem 20. The front portion 8 extends below the waistline 12 to include a tail 13 that terminates at a point intermediate the length of the back portion and is stitched to the back portion down to the bottom of the tail 13. The arm holes are suggested at 14.

The front 15 of the skirt portion is sewn to the back portion 7 of the garment along the lower portion of the seam 9 approximately from the point 16 downward to the bottom hem of the garment. A belt 17 may be attached along the top of the front portion 15 of the skirt, as by stitching 21, but is free of the back portion of the garment. The belt 17 may be tied at the back, as suggested at 18. The belt 17 is not attached to the front 8 of the waist or bodice, nor to the back portion 7.

It will be noted that the edge portions of the skirt front 15, from the points 16 upward, are free from attachment to either the front portion of the waist or bodice or the back portion 7 of the garment (except indirectly by the belt 17). This provides in effect a loose bib 19 in front of the area where progressive increase in the girth takes place during pregnancy.

In the use of my present garment, the skirt is self-adjusting by reason of the loosening of the bib 19. As the pregnancy advances, the bib 19 may be swung forward and the angle or gap increased between the lateral edges of the bib 19 and the substantially vertical, side seam 9. It is to be understood that the tail 13 is initially made with sufficient material to take care of whatever expansion of the girth is necessary. In the earlier stages, the front portion 8 may be gathered, within the belt 17, which gathering becomes less and less in the latter stages. The lower edge of the tail 13 "hikes" up in the latter stages. The beginning of this change of position is shown at 13 in Fig. 2.

It is believed that it is clear without further illustration that the belt 17 may be held by any suitable fastening means, instead of tying same, and moreover, that the skirt may also be either a wrap-around or a draw-string type, providing the skirt is fastened to the waist or bodice at the back only and has a loose tail on the waist or bodice at the front.

In addition, it is believed clear that the waist or bodice (both of which are included in the term "waist" in the hereto appended claims) may open down the front or back, if desired, and that the waist or bodice may be eliminated above the line 12, and provide a garment in which all the features shown at or below such line are included.

While I have illustrated and described what I

now regard as the preferred embodiment of my invention, the construction is, of course, subject to modifications without departing from the spirit and scope of my invention. I, therefore, do not wish to restrict myself to the particular form of construction illustrated and described, but desire to avail myself of all modifications that may fall within the scope of the appended claims.

Having thus described my invention, what I claim and desire to secure by Letters Patent is:

1. A maternity garment comprising an upper back portion and a back skirt portion, a front upper waist portion having a lower extension terminating a substantial distance below the waistline and having its side edges secured to the side edge portions of the back, said upper front waist portion being more than one-half of the circumference of the garment at the waistline so as to provide fullness thereat, a front skirt portion for said garment extending downwardly from the waistline, said front skirt portion being connected to said back portion along its vertical marginal edges from a point adjacent the bottom of said front waist portion to the bottom of the garment, the upper side edges of said lower front skirt portion being free and unattached to form a bib overlying the lower part of the upper front waist portion, and being adapted for adjustment in a direction away from the back of the garment as the full upper waist portion is expanded to accommodate different sizes of girth, and means for adjustably securing said bib about the waist.

2. A maternity garment comprising an upper back portion and a back skirt portion, a front upper waist portion having a lower extension terminating a substantial distance below the waist-

line and having its side edges secured to the side edge portions of the back, said upper front waist portion being more than one-half of the circumference of the garment at the waistline so as to provide fullness thereat, a front skirt portion for said garment extending downwardly from the waistline, said front skirt portion being connected to said back portion along its vertical marginal edges from a point adjacent the bottom of said front waist portion to the bottom of the garment, the upper side edges of said lower front skirt portion being free and unattached to form a bib overlying the lower part of the upper front waist portion, and being adapted for adjustment in a direction away from the back of the garment as the full upper waist portion is expanded to accommodate different sizes of girth, and a belt secured to the upper marginal edge of said bib and being adapted to extend about the back of the garment, the free ends of the belt being adapted to be adjustably secured together to permit the girth of the garment to be extended.
